UNITED STATES PATENT OFFICE.

ARTHUR NEWTON-SMITH, OF LONDON, ENGLAND.

SHUTTLE-CHECKING MECHANISM OF LOOMS.

1,315,608.

Specification of Letters Patent. Patented Sept. 9, 1919.

Application filed March 8, 1919. Serial No. 281,437.

To all whom it may concern:

Be it known that I, ARTHUR NEWTON-SMITH, a subject of the King of Great Britain and Ireland, and resident of London, England, have invented new and useful Improvements in or in Connection with the Shuttle-Checking Mechanism of Looms, of which the following is a specification.

This invention relates to improvements in or in connection with the shuttle checking mechanism of looms and the invention has for its objects the provision of means by which (a) the braking effort applied to the shuttle when entering the shuttle box is capable of regulation to suit the weight and speed of the shuttle; (b) the resistance offered to the delivery of the shuttle from the shuttle box is maintained at a constant value; and (c) destroy the momentum of the shuttle when moving in one direction and assist in its guidance when moving in the other direction under the influence of a picker.

In accordance with this invention, the momentum of the shuttle is destroyed by contact with the swell which is moved inwardly by the shuttle against a controllable opposition consisting of a dash pot and spring.

Further in accordance with this invention the delivery of the shuttle from the shuttle box is effected against resistance due to the action of the spring of the controllable opposition on the swell.

Referring now to the accompanying drawings:—

Fig. 1 is a sectional plan view of a shuttle box; and

Fig. 2 is a similar view of a modification.

Referring to Fig. 1,

1 is the swell which, as usual, comprises a plate of wood or metal pivotally mounted at one end on the back 2 of the shuttle box. The swell 1 is subject to the action of means which cause it to exert a braking action and destroy the momentum of a shuttle entering the shuttle box and a steadyng action and assist in the guidance of the shuttle when moving in the other direction under the influence of a picker.

50 The swell 1 has at one end a vertically disposed pin 3 and the back 2 has slots 4 at right angles to the faces thereof with which the pin 3 engages. The pivotal mounting described provides for a compound movement of the swell, viz; the ordinary pivoting or angular movement and a movement

or a change of position as a whole in relation to the shuttle 5, and the back 2. 6 is a pin mounted on the rear face of the swell 1 and extending therefrom through a hole in the back 2 to the rear of the shuttle box where it contacts or is connected with a lever 7 pivotally mounted at one end on the rear face of the back 2. The lever 7 is subject to the pressure of a spring 8 which is also mounted on the rear face of the back 2 and which tends to hold the lever 7 and swell 1 in the position shown in full lines. The pressure of the spring 8 on the lever 7 is adjustable, and adjustment is effected by screwing up or down the bolt 9. Regulation of the spring pressure may be effected otherwise.

10 is the rod of a piston 11 contained and movable within a cylinder 12 closed at one end and mounted with its open end against the rear face of the back 2. The free or outer end of the piston rod 10 is guided by and in a sleeve 15 mounted in the back 2. 14 is a slot formed through the wall of the cylinder 12 and extending longitudinally thereof from the open end. The lever 7 extends through the slot 14 within the cylinder 12 and its free or outer end enters and engages a hole or recess in the piston rod 10. The piston 11 and cylinder 12 form an air dash pot and the inward movement of the piston is controlled by a needle valve 13.

From the foregoing it will be seen that when a shuttle 5 enters the shuttle box, it engages the swell 1 and causes it to turn about its pivotal mounting 3, 4 and also to move as a whole inward against the conjoint actions of the spring 8 and dash pot 11, 12. The resistance to movement of the swell 1 offered by the dash pot 11, 12 and by the spring 8 is regulated by the needle valve 13 and bolt 9 respectively, and the greater this resistance the greater is the braking action of the swell 1 on the shuttle 5. The dash pot 11, 12 is only operative when the swell 1 is moving inwardly, but the spring 8 is operative at all times. The pressure of the spring 8 on the swell 1 causes the swell 1 to offer some resistance to movement of the shuttle under the influence of a picker. This resistance is reduced as much as is possible and the spring is adjusted so that its pressure is only sufficient to pull back the piston 11 within the cylinder 12 and reset the swell 1 and to

keep the shuttle steady when moving under the influence of a picker.

In the modification illustrated in Fig. 2, the swell 1 is mounted directly on the lever 5 which is pivotally mounted on a bracket 16 secured to the back 2 and forming also a carrier for the spring 8.

In some constructions in accordance with this invention, the swells may be provided 10 with horizontal projections and thus act as screeds and when so employed they may be mounted so as to permit of vertical adjustment.

What I claim is:

- 15 1. In a loom, shuttle checking mechanism comprising the combination with a shuttle box and a swell mounted thereon, of a dash pot and spring both operatively connected to the swell.
- 20 2. In a loom, shuttle checking mechanism comprising a shuttle box, a swell carried by said shuttle box, a dash pot, a lever connecting said dash pot and said swell, and a spring arranged to bear on the lever.
- 25 3. In a loom, shuttle checking mechanism comprising a shuttle box, a swell car-

ried by said shuttle box, a dash pot, a lever connecting said dash pot and said swell, a spring arranged to bear on the lever, and 30 means for regulating the tension of the spring on said lever.

4. In a loom, shuttle checking mechanism comprising a shuttle box, a lever pivotally mounted on the exterior of said shuttle box, a swell connected with said lever and arranged to be engaged by the shuttle in the movement of the latter, a dash pot operatively connected with one end of said lever, and a spring mounted on said shuttle 40 box and arranged to bear on said lever.

5. In a loom, shuttle checking mechanism comprising a shuttle box having an opening, a swell mounted in said opening, a lever pivotally carried by said shuttle box, 45 said swell being mounted directly on said lever, a dash pot operatively connected with one end of said lever, a spring carried by said shuttle box and arranged to bear on said lever, and means for regulating the 50 tension of the spring on the lever.

Dated this seventeenth day of February, 1919.

ARTHUR NEWTON-SMITH
